HENRY A. ADAMS, OF NEW YORK, N. Y., ASSIGNOR TO HIMSELF
AND G. E. HILL, OF SAME PLACE.

Letters Patent No. 86,797, dated February 9, 1869.

IMPROVEMENT IN GUARD FOR DOOR-KEYS.

The Schedule referred to in these Letters Patent and making part of the same.

To all whom it may concern:

Be it known that I, HENRY A. ADAMS, of the city, county, and State of New York, have invented a new, and improved Burglar and Spy-Proof Key-Guard; and I do hereby declare that the following is a full and exact description thereof, reference being had to the accompanying drawings, forming part of this specification, and to the letters of reference marked thereon.

The object of my invention is to provide a burglar and spy-proof key-guard for the use of guests of hotels and boarding-houses, for their protection against burglars and hotel-thieves, and also for all residents, for the same purpose.

The nature of my invention consists in providing a straight bar, which may be either square, round, or octagonal, upon one end of which is a cross-head that is designed to enter the key-hole under the key. Upon this bar is another cross-head, made to fit closely, but so as to move freely backward and forward upon the said bar, which, when in proper position, may be fixed in its place by means of a thumb-screw, with which it is provided, and also a movable disk, which is designed to cover the key-hole.

At each end of the movable cross-heads are hooks secured by means of a hinge or joint, so as to allow them to move, so that, taking the cross-head and hooks together, they form a sort of bifurcated movable cross-head, and when the key is introduced into the key-hole, and the stationary cross-head, and a spike or prong on the face of the disk, are also introduced, the shank of the key resting on a notch or slot provided on the edge of the disk, these hooks are introduced into the ring or bow of the key, and when thus engaged it is impossible to turn the key from the opposite side of the door, while the movable disk being now close to the key-hole, renders it impossible for a person outside of the door to see through the key-hole into the room.

To enable others skilled in the art to make and use my invention, I will proceed to describe its construction and operation.

Figure I represents a side elevation of my improved burglar and spy-proof key-guard.

Figure II represents a plan view of the same engaged with a door-key.

Letters of like name and kind refer to like parts in each of the figures.

A represents a straight steel bar, or it may be made of any suitable metals and of proper dimensions.

At one end of the said bar A, is a cross-head, B,

made so as to enable it to enter through the key-hole, underneath the key, after the key has been turned partially round out of the way, so as to allow the cross-head B to enter the lock.

C is the movable cross-head, to which are attached the hooks D D, by any suitable joint or hinge, E, and which may be firmly secured to the bar A by means of the thumb-screw F, when the said cross-head has been adjusted by moving it along the bar A, so as to correspond with the length of the key G, to which it may be desired to attach it.

I is a movable disk placed upon the bar A, provided with a notch, K, in which the shank of the key rests, and a spike or prong, L, designed to enter the key-hole.

It will be seen that when the key G has been inserted into the key-hole, inside the door, and turned so as to lock the door, the cross-head B is placed within the key-hole as far as it will go; the bar A is then brought alongside the shank of the key, which rests in the notch K on the edge of the disk, the prong or spike L being introduced into the key-hole, when the hooks D D are attached to the ring or bow of the key, as seen at H, and the cross-head C is moved along the bar A as far as it will go in the direction of the cross-head B, when the cross-head C is firmly fixed to the bar A by means of the thumb-screw F. The guard is then in position, and it will be found impossible for a person outside the door to turn the key in the lock, or to push it out, or to introduce any implement into the key-hole with which to pick the lock, while the disk I will so cover the key-hole as to prevent the possibility of seeing into the room through the key-hole from without.

The advantages of my invention will be readily seen, for the reason that it is cheap and simple in its construction, and can be carried in the pocket or elsewhere without inconvenience, while it is well adapted for the purpose for which it is designed, and can be applied without causing the least injury to the door.

Having thus described my invention,

What I claim as new, and desire to secure by Letters Patent of the United States, is—

The combination of the bar A, provided with the cross-head B, disk I, prong L, cross-head C, hooks D, and set-screw F, all arranged to operate substantially as and for the purposes set forth.

H. A. ADAMS.
